UNITED STATES PATENT OFFICE.

JEAN PIERRE HEUCHEL, OF ROUEN, FRANCE.

CARBURETING APPARATUS.

Application filed May 4, 1923. Serial No. 636,677.

To all whom it may concern:

Be it known that I, JEAN PIERRE HEUCHEL, a citizen of the Republic of France, residing at Rouen, France, have invented 5 certain new and useful Improvements in Carbureting Apparatus, of which the following is a specification.

My invention relates to an improved carbureting apparatus in which, contrary to 10 the known methods, the air inlet is situated between the source of liquid fuel and the engine. In such an arrangement, there will be produced a zone of depression, the degree 15 of depression and the distance of such zone from the liquid spray being variable and depending directly upon the section of the air inlet and the speed of the engine.

This withdrawal on the reaction principle will cause air and fuel to be drawn in, 20 whereof the proportions will vary in like manner; and this will provide for a fuel mixture whose composition is constant for all speeds and all amounts of fuel admitted.

The appended drawings, which are given 25 by way of example, illustrate an apparatus in which the carburetor proper is arranged both vertically and horizontally.

Figs. 1 and 2 relate to the vertical apparatus and show sections of the same on the 30 lines I—I and II—II.

Fig. 3 is a front view of one of the flanges of the barrel.

Fig. 4 relates to the horizontal apparatus and is a sectional view of the same.

Fig. 5 is a section of the latter apparatus on the line V—V.

Referring to Figs. 1 and 2, 1 designates the float feed chamber which is closed at the top by a cover 2 serving as the base of the carburetor proper. A tube 3 is screwed 40 into an aperture in the centre of the said cover and is submerged to the proper level in the said chamber, said tube being coaxial with and serving to guide the float 30. Into the top of the tube 3 is screwed a smaller 45 tube 36 forming a sprayer. The radial ducts 40 formed through the sprayer tube open into the space 41 which has a tapered, conical or like shape, and they connect the bore 50 of the sprayer with a mixing chamber 4 provided at the lower part of the body of the carburetor.

The apertures 32 formed in the top of the main tube 3 are connected with the atmosphere by the air inlet ports 5 and ensure 55 the initial supply of air, producing an emul-

sion which is at first rich in fuel but whose degree becomes reduced in additional chamber 4 due to the use of the air inlets 33. A horizontal partition 34 which is traversed 60 by the vertical conduits 7 forms the upper wall of the chamber 4. The said partition is suitably recessed in order to receive the horizontally mounted barrel 13 which extends 65 through the carburetor body 11 and is held in place on one side by the integral flange 42 and on the other by the slidible flange 43, the latter being pressed against the body by the spring 44 which is interposed between the said flange and a nut 45 secured 70 to the end of the axle of the said barrel.

The barrel is rotated by the handle 17 and has three apertures 15 whereof two are adapted to co-operate directly with the conduits 7 while the third, which is of large 75 size, connects the interior of the barrel with the upper part of the body through which the fuel mixture proceeds to the engine.

Apertures 12 (Fig. 1) are formed in the walls of the carburetor body just above the 80 partition 34; they cooperate with apertures 46 formed in the flanges 42, 43 which are adapted to be brought into and out of registration therewith during the rotation of said flanges, the arrangement being such that 85 registration takes place at the same time that the apertures 15 coincide with the conduits 7. The sprayer tube 36 extends upwardly to a point somewhat below the barrel 13, and the liquid fuel which rises in the 90 said tube when the engine is running at reduced speeds is enabled to enter the barrel through the aperture 47 in said barrel which is so arranged that the conduits 7 are closed 95 when this takes place as may be readily observed.

The operation is as follow:

When the engine is started, the conduits 7 and apertures 12 are closed, and the sprayer tube 36 is open by means of the aperture 47, so that the engine can withdraw through the said tube the gasoline contained in the 100 said float chamber, and (through the ducts 40) the air admitted by the apertures 32 and the inlets 33. To proceed to the normal 105 operation of the engine, it is simply necessary to turn the barrel by means of the handle 17, thus closing the tube 36 and opening the conduits 7; the gasoline will then be drawn through the ducts 40 into the 110 mixing chamber 4 where it meets the air admitted through the lower ducts 32, form-

ing a rich emulsion which is thereupon agitated and diluted in said chamber before passing through the conduits 7 into the barrel 13.

5 When issuing from the latter, the resulting mixture will meet with the air entering through the apertures 12 and an energetic mixing action takes place here. The quantity of air thus admitted will obviously 10 increase upon turning the handle, i. e., the extent of opening of the conduits 7 is augmented, so that the proportion of fuel and air remains constant, thus insuring the maximum efficiency for all degrees of admission.

15 In the modification shown in Fig. 4, the same characteristics are observed. But the tube 3 has at the lower part a calibrated orifice 48 situated a few centimetres above 20 the bottom of the chamber 1; the said tube is also directly connected at the upper part with the conical space 41, with which latter the apertures 32 also communicate. The sprayer tube 36 still enters the main tube 3 25 but is not screwed thereto, being on the contrary surrounded by an annular passage; in this case it is secured to the annular partition 34 and is directly connected with the chamber 4 through the radial ducts 37.

30 Above the partition 34 the main or body part 11 has its axis horizontal and is arranged so as to contain the barrel 13 which is closed at one end and open at the other. The said barrel is held by a milled nut 49 35 and has an extension 50 which is secured to the control handle 17. As before, the walls of the barrel are provided with the apertures 15 co-operating with the conduits 7; the aperture 47 is also employed and 40 serves the same purpose as before, and the apertures 14 co-operating with the apertures 12 provided in the body 11 and serving as the main air inlets.

45 In the embodiment shown in Fig. 4 there is also disposed in front of the orifices 12 a tapered member 35 for concentrating the mixture at the middle part of the barrel.

50 The operation of this modified form is similar to the preceding. When running at slow speed, the gasoline rises through the tube 36 and enters the barrel, meeting with admitted air at the level of the ducts 37. In normal operation, the said tube is closed and the gasoline passes directly from the 55 main tube 3 through the conical space 41 into the mixing chamber 4 and thence through the conduits 7 into the barrel 13, and proceeds from this point to the engine; during its passage, it meets with the successive air inlets 5, 33 and 12 so as to form an emulsion which becomes weaker in fuel as it approaches the outlet of the carbureting apparatus.

60 Obviously, the said invention is susceptible of modifications in detail without de-

parting from its spirit, and in particular, the arrangement of the barrel in the body of the apparatus, which is here illustrated by way of example, can be carried out in any suitable manner. Further, a horizontal 70 carbureting apparatus may be used which comprises a gasoline feed analogous to the one described for the vertical apparatus and vice versa.

75 I claim:

1. In a carburetor, the combination of a float feed chamber; a casing or body mounted thereon and providing a mixing chamber and air inlets opening into the same; a main fuel tube fitting at its upper end in 80 the casing immediately below the mixing chamber and projecting at its lower portion into the fuel in the float chamber, said tube having an enlarged mouth at the upper end of its bore; a sprayer tube having its 85 lower portion projecting into the main tube and also having an enlargement which is disposed in said mouth but spaced from the wall thereof to form an intermediate annular fuel passage of large diameter communicating at its lower end with the bore of the main tube and opening at its upper end into the mixing chamber; a partition in 90 said casing forming the top wall of the mixing chamber and provided with conduits opening thereinto; a throttle valve mounted in the casing immediately above said partition and having an aperture individual to each conduit and adapted to be brought into and out of registration therewith, and another aperture adapted to be brought into and out of registration with the end of the bore of the sprayer tube; and means for 95 operating said throttle valve.

100 2. In a carburetor, the combination of a float feed chamber; a casing or body mounted thereon and providing a mixing chamber and air inlets opening into the same; a main fuel tube fitting at its upper end in 105 the casing immediately below the mixing chamber and projecting at its lower portion into the fuel in the float chamber, said tube having an enlarged, inverted conical mouth at the upper end of its bore; a sprayer tube having its lower portion projecting into the main tube and also having 110 an enlargement of inverted conical shape which is disposed in said mouth but spaced from the wall thereof to form a tapered, annular fuel passage of large diameter 115 communicating at its lower end with the bore of the main tube and opening at its upper end into the mixing chamber; a partition in said casing forming the top wall of the mixing chamber and provided with conduits opening thereinto; a throttle valve mounted in the casing immediately 120 above said partition and having an aperture individual to each conduit and adapted to be brought into and out of registration 125

therewith, and another aperture adapted to be brought into and out of registration with the end of the bore of the sprayer tube; and means for operating said valve.

5. A carburetor, according to claim 1, in which the air inlets are formed laterally in the side wall of the mixing chamber at a point immediately above the enlargement of the sprayer tube; and in which said wall is formed with lower air inlets that communicate with the lower portion of the annular fuel passage.

10. A carburetor, according to claim 1, in which the side wall of the mixing cham-

ber is formed with air inlets that communicate with the lower portion of the annular fuel passage, and with other air inlets that open laterally into said chamber at a point immediately above the enlargement of the sprayer tube; and in which said sprayer tube is formed with radial ducts that open at their inner ends into its bore and are in communication at their outer ends with the interior of the mixing chamber.

15. In testimony whereof I affix my signature.

JEAN PIERRE HEUCHEL.
